UNITED STATES PATENT OFFICE.

RICHARD B. DWYER, OF WEST DULUTH, MINNESOTA, ASSIGNOR OF ONE-HALF TO
CHARLES EDWARD BALL, OF WEST DULUTH, MINNESOTA.

HINGE.

1,145,759.

Specification of Letters Patent.

Patented July 6, 1915.

Application filed April 19, 1915. Serial No. 22,442.

To all whom it may concern:

Be it known that I, RICHARD B. DWYER, a citizen of the United States, residing at West Duluth, in the county of St. Louis and 5 State of Minnesota, have invented certain new and useful Improvements in Hinges; and I do hereby declare the following to be a full, clear, and exact description of the invention, such as will enable others skilled in 10 the art to which it appertains to make and use the same.

This invention relates to hinges, and the primary object of the invention is to provide a hinge for use upon storm doors, windows, 15 or ordinary doors, which is comparatively simple in construction, and in which the pintle is removably and rotatably mounted within a thimble or sleeve, so that upon endwise movement of the pintle, it may be removed 20 from the pintle sleeve or knuckle.

Another object of this invention is to provide means for preventing the accidental displacement of the pintle with respect to the knuckle or sleeve.

25 With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the 35 several views, and in which:—

Figure 1 is a view, showing the application of the improved hinge to a door or similar structure, Fig. 2 is a sectional view, on the line 2—2 of Fig. 1. Fig. 3 is a side elevation of the improved hinge used for hanging or suspending a storm window or the like which swings in a substantially vertical plane, and Fig. 4 is a detail perspective view of the knuckle.

45 Referring more particularly to the drawings, 1 designates a permanent support, such as a window sill, door casing or the like, and 2 indicates the swingable member, such as a window or door. The casing or permanent 50 member 1 has a plate 5 secured thereto, in any suitable manner, such as by screws or analogous fastening devices 6. The plate 5 has a pintle sleeve or knuckle 7 formed thereupon and projecting outwardly from 55 the outer face of the same, which knuckle

is provided with a central bore 8, and a transversely extending slot 9 which is formed therein substantially equi-distant of its ends, and positioned in a horizontal plane. A vertically extending slot 10 communicates with the horizontally disposed slot 9 and also with the upper end of the knuckle, as is clearly shown in Fig. 1 of the drawings. The plate 5 is provided with a groove 11 formed in the face thereof, which forms an approach for the upper open end of the knuckle 7. The approach 11 is arcuate in cross section, and tapers outwardly as it extends downwardly toward the upper end of the knuckle, for facilitating the guiding of the spindle or pintle 12 into the bore 8 of the knuckle.

The pintle 12 is formed upon the outer end of an arm 14 and extends transversely thereto. The arm 14 is formed upon a plate 15, which is adapted for attachment to the swingable structure 2 by means of screws or analogous fastening devices 16. The arm 14 extends outwardly from the outer surface of the plate 15, being positioned substantially parallel to and outwardly from the outer surface of the plate, as is clearly shown in Fig. 2 of the drawings.

The sleeve 7 has a transversely extending ear or lug 17 formed thereon, to which is pivotally connected a swinging sleeve cover 18. The cover 18 is provided for swinging into engagement with the upper end of the knuckle 7, for forming a closure therefor for preventing accidental displacement of the 90 pintle 12 within the knuckle, and also for preventing the accumulation of dust, dirt or the like within the bore of the knuckle. The cover 18 is pivotally connected to the lug 17 by a pin 19.

In Fig. 3 of the drawings, the improved hinge is illustrated as a hanger for storm windows or other articles, which are hinged at their top edges and swing substantially in vertical planes. Fig. 4 also shows the 100 knuckle used when the device is employed as a hanger. This construction is identical with the construction of the knuckle and supporting plate, illustrated in Fig. 1, with the exception of the fact that the slot 20, 105 which is formed horizontally therein, extends about only a part of the circumference of the knuckle, while in the knuckle 7, the slot extends about practically the entire circumference of the same, as is clearly shown 110

in Fig. 2 of the drawings. The knuckles are provided with transversely extending alining openings 21 and 22, which are adapted for receiving the ends of pins for engaging the upper ends of the pintles, for preventing accidental displacement of the pintles with respect to the knuckle, in case the covers 18 should become broken.

In mounting the swingable member 10 hingedly upon the permanent member, the doors 18 are swung outwardly, and the pintles 12 are moved until they engage the groove 11 of the plate 5, after which the downward movement of the swingable member will properly guide the pintles within the knuckles, and support the swingable member by the permanent member for swinging or hinged movement with respect thereto. During the inserting movement of 20 the pintles within the knuckles, the arms 14 pass downwardly through the vertical slots 10.

In reducing the invention to practice, certain minor features of construction, combination, and arrangement of parts may necessitate alterations to which the patentee is entitled, provided such alterations are comprehended within the scope of what is claimed.

30 What is claimed is:—

1. In a hinge, a plate for attachment to a permanent member, said plate having a knuckle formed thereupon, a swingable member, a plate secured to said swingable member, an arm secured to said plate and extending outwardly therefrom, a pintle formed upon the outer end of said arm and extending transversely thereto, said pintle adapted for seating in said knuckle for 35 hingedly connecting said swingable member and said permanent member, said attaching plate being provided with an arcuate groove forming an approach for guiding the movement of said pintle into said knuckle.

40 2. In a hinge, a plate for attachment to a

permanent member, said plate having a knuckle formed thereupon, a swingable member, a plate secured to said swingable member, an arm secured to said plate and extending outwardly therefrom, a pintle formed 50 upon the outer end of said arm and extending transversely therethrough, said pintle adapted for seating in said knuckle for hingedly connecting said swingable member and said permanent member, said attaching plate being provided with an arcuate groove 55 forming an approach for guiding the movement of said pintle into said knuckle, a cover pivotally connected to the upper end of said knuckle and adapted for swinging 60 movement above the end of the knuckle.

3. In a hinge, an attaching plate for attachment to a permanent member, a knuckle formed upon and projecting outwardly from said attaching plate, said knuckle being provided with a horizontally disposed slot, a vertical slot communicating with said horizontally disposed slot, an attaching plate for attachment to the swingable member, an arm formed upon said second named attaching 65 plate and extending outwardly from one edge thereof, a pintle formed upon the outer end of said arm and adapted for seating in said knuckle, said vertical slot forming a guideway for guiding the movement of said 70 arm downwardly therethrough into said horizontally disposed slot, said first named attaching plate being provided with an arcuate groove forming an approach for the upper open end of said knuckle, a cover pivotally connected to said attaching plate for swinging movement above the upper open 75 end of said knuckle.

In testimony whereof I affix my signature in presence of two witnesses.

RICHARD B. DWYER.
